(57) **CLAIM**

The ornamental design for a bottle with cap, substantially as shown and described.

DESCRIPTION

FIG. 1 is a perspective view of the bottle with cap of the present invention, with the cap removed for clarity of illustration;

FIG. 2 is a perspective view of the bottle with cap of FIG. 1 with the cap on;

FIG. 3 is a top plan view of the bottle with cap as shown in FIG. 2;

FIG. 4 is a bottom plan view of the bottle with cap thereof; FIG. 5 is a front elevational view of the bottle with cap thereof;

FIG. 6 is a rear elevational view of the bottle with cap thereof;

FIG. 7 is a front elevational view of the bottle with the cap removed as shown in FIG. 1;

FIG. 8 is a rear elevational view of the bottle with cap removed as shown in FIG. 1; and,

FIG. 9 is a side view of the bottle with the cap removed as shown in FIG. 1.

The solid line at the top inside edge of the pour spout lip is the boundary of the claim.

The broken lines shown in FIGS. 1, 4, and 7-9 are for illustrative purposes only and form no part of the claimed design.
